(57) **CLAIM**

We claim the ornamental design for a touchpad for a notebook computer, as shown and described.

DESCRIPTION

FIG. 1 is a perspective view of a touchpad for a notebook computer, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the touchpad for a notebook computer in a partially-closed position; and,

FIG. 9 is a perspective view of the touchpad for a notebook computer in another partially-closed position.

The portions of the touchpad for a notebook computer shown in broken lines form no part of the claimed design. The dot-dash lines in FIGS. 1, 6, 8, and 9 represent a boundary of the claimed design and form no part of the claimed design.
